The ornamental design for a chamber and contact area for a battery charger, as shown and described.

(21) Appl. No.: **29/314,347**

DESCRIPTION

(22) Filed: **Mar. 23, 2009**

FIG. 1 is a top, front perspective view of a chamber and contact area for a battery charger showing our new design; FIG. 2 is a cross-sectional view thereof, taken along lines “2—2” in FIG. 4;

FIG. 3 is a cross-sectional view thereof, taken along lines “3—3” in FIG. 4;

FIG. 4 is a cross-sectional view thereof, taken along lines “4—4” in FIG. 3;

FIG. 5 is a cross-sectional view thereof, taken along lines “5—5” in FIG. 3; and,

FIG. 6 is a cross-sectional view thereof, taken along lines “6—6” in FIG. 4.

The even-broken line shown in the drawings is included for the purpose of illustrating environmental structure and forms no part of the claimed design. The dash-dot line represents the boundary of the claimed design.
